(57) **CLAIM**

The ornamental design for a data processing reader, as shown and described.

DESCRIPTION

FIG. 1 is a top plan view of a data processing reader in a collapsed, folded condition, showing our new design.

FIG. 2 is a top perspective view of the reader shown in FIG. 1.

FIG. 3 is a side elevational view of the reader shown in FIG. 1, it being understood that the opposite side is a mirror image thereof.

FIG. 4 is a bottom plan view of FIG. 1.

FIG. 5 is a front elevational view of FIG. 1.

FIG. 6 is a rear elevational view of FIG. 1.

FIG. 7 is a top plan view of the reader shown in FIG. 1, with a handle thereof in an unfolded condition.

FIG. 8 is a bottom perspective view of the reader shown in FIG. 7.

FIG. 9 is a side elevational view of the reader shown in FIG. 7 after being turned by 180°, with the opposite side as a mirror image thereof.

FIG. 10 is a bottom plan view of FIG. 7.

FIG. 11 is a reduced top plan view of the reader shown in FIG. 7 after the handle has been fully extended from a collapsed position shown in FIG. 7.

FIG. 12 is a reduced side elevational view of the reader shown in FIG. 11 after being turned by 180° with the opposite side being a mirror image thereof.

FIG. 13 is a reduced bottom plan view of FIG. 11; and,

FIG. 14 is a reduced bottom perspective view of the reader shown in FIG. 11.
